RICHARD KORET, OF NEW YORK, N. Y., ASSIGNOR TO KORET, INC., OF NEW YORK, N. Y.,
A CORPORATION OF NEW YORK

DESIGN FOR A HAND BAG FRAME OR ANALOGOUS ARTICLE

Application filed January 30, 1932. Serial No. 42,677. Term of patent 3½ years.

To all whom it may concern:

Be it known that I, RICHARD KORET, a citizen of the United States of America, and residing at New York city, in the county of New York and State of New York, have invented a new, original, and ornamental Design for Hand Bag Frame or Analogous Article, of which the following is a specification, reference being had to the accompanying drawings, forming part hereof.

Figure 1 is a side elevation of a hand bag frame or analogous article showing my new design.

Fig. 2 is a top plan view, and

Fig. 3 is a sectional view taken substantially on the line 3—3 of Fig. 1.

The dominant feature of my design consists in the latch device mounted upon the frame.

I claim:

The ornamental design for a hand bag frame or analogous article substantially as shown and described.

RICHARD KORET,
